(57) **CLAIM**

The ornamental design for a wedge insert, as shown and described.

DESCRIPTION

FIG. 1 is a front perspective view of a wedge insert comprising the new design;

FIG. 2 is a back perspective view of the design of FIG. 1; FIG. 3 is a front elevational view of the design of FIG. 1, where the back elevational view is a mirror image thereof; FIG. 4 is a top view of the design of FIG. 1;

FIG. 5 is a bottom view of the design of FIG. 1;

FIG. 6 is a right elevational view of the design of FIG. 1; and,

FIG. 7 is a left elevational view of the design of FIG. 1. The relatively light unevenly broken lines represent contour and are not surface decoration.
